Primary Examiner — Steven J Czyz

CLAIM

The ornamental design for a pull-out pill box, as shown and described.

DESCRIPTION

FIG. 1 is a perspective view of a pull-out pill box showing my new design;

FIG. 2 is a front perspective view thereof;

FIG. 3 is a back side view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof;

FIG. 9 is a perspective view when the right side lid is opened; and,

FIG. 10 is another perspective view when the left side lid is opened.

1 Claim, 10 Drawing Sheets
